UNITED STATES PATENT OFFICE.

JOHN H. MONTGOMERY, OF NEW YORK, N. Y.

CLOSURE FOR BOTTLES, JARS, AND OTHER RECEPTACLES.

1,427,694.

Specification of Letters Patent. Patented Aug. 29, 1922.

Application filed December 24, 1919. Serial No. 347,119.

To all whom it may concern:

Be it known that I, JOHN H. MONTGOMERY, a citizen of the United States, residing at New York, in the county of New York and 5 State of New York, have invented certain new and useful Improvements in Closures for Bottles, Jars, and Other Receptacles, of which the following is a specification.

This invention relates to closures for bottles, jars and other receptacles, and particularly to the type of closures known as "sprinkler tops." These sprinkler tops are generally of metal, perforated as to that portion which covers the mouth of the receptacle, 15 and with a threaded skirt that engages with threads formed on the exterior mouth portion of the receptacle, to hold the cap in position.

Particularly in cases where the receptacle 20 is made of glass and the cap of metal, the fit of the cap must be somewhat loose, in view of the possibility of breakage; consequently there is likelihood of the escape of the receptacle-contents by way of the space 25 between the neck of the receptacle and the interior wall of the closure skirt; also of evaporation of the receptacle-contents, and dissemination of any odorous principles held by the contents. And this leakage takes 30 place, even though valve means be provided for closing the perforations of the cap, or a separate paper or other cap be applied over the sifter cap.

In many instances, also, though the leakage 35 age of the contents, etc., is not of particular importance, a very objectionable feature is that the access of air to the interior of the receptacle, made possible by the loose fit between the cap and receptacle has a deleterious effect on the contents. Furthermore, 40 the loose fit before mentioned is objectionable per se, because the cap is apt to come off entirely, due to vibration, etc.

The closure hereinafter described aims to 45 overcome the objections above noted, and at the same time provides a closure which is simple and economical to manufacture.

Other objects and aims of the invention, 50 more or less broad than those stated above, together with the advantages inherent, will be in part obvious and in part specifically referred to in the course of the following

description of the elements, combinations, arrangements of parts, and applications of principles constituting the invention; and 55 the scope of protection contemplated will appear from the claims.

In the accompanying drawings, which are to be taken as part of this specification, and in which I have shown merely a preferred 60 form of embodiment of the invention, Figure 1 is a view, partly in side elevation, and broken away to show the remainder in section, illustrating the mouth portion of a bottle or receptacle; Figure 2 is a top plan view 65 of the subject-matter of Figure 1, showing the metallic or outside cap partly broken away and in section to reveal the supplementary non-metallic cap thereunder; and Figure 3 is a perspective view of the supplementary cap. 70

Referring to the numerals on the drawings, there is shown at 4 a glass receptacle, with a mouth portion 5. Where a threaded cap or closure is to be used the neck portion 75 of the receptacle below the mouth is threaded, as indicated, and a cap or closure 6, which may be of metal, has a part 7 that covers the mouth, and a depending skirt 8 threaded to correspond with the threads on 80 the receptacle. Between cap 6 and the receptacle is a supplementary cap 9 (Fig. 3), preferably of compressible material, with a portion 10 stretched tightly over the receptacle mouth, and a skirt 11 that conforms to 85 the threaded exterior neck of the receptacle to hold the supplementary cap firmly in position. I prefer to use for the purposes of this inside closure a cap of suitable size and shape, made of hydrated cellulose or equivalent material, which is applied in a wet condition over the mouth of the receptacle, and upon drying contracts and so fixes itself in 90 position as indicated in Figure 1. Thus a cap is provided which holds its position, and which substantially seals the receptacle. 95

The closure hereinafter described aims to 100 overcome the objections above noted, and at the same time provides a closure which is simple and economical to manufacture. Other objects and aims of the invention, more or less broad than those stated above, together with the advantages inherent, will be in part obvious and in part specifically referred to in the course of the following

so provides a packing to hold the outside cap against coming off accidentally, and also of course prevents escape of the receptacle contents by way of the space between bottle 5 neck and outside cap, or the passage of air into the receptacle. These results are obtained without covering or concealing in any way the outside cap, which is often ornamental in character, and which protects the 10 cap 9.

In some cases the outside cap is perforated, as indicated at 12, for the sifting or sprinkling of powder contained in the receptacle, the perforations being controlled by 15 valve devices, if desired. In such instances the receptacle may remain sealed, safe against loss or deterioration, until the contents are to be used, when, by means of a pin inserted through the open perforations of 20 the outside cap, the inside cap may be pierced (these perforations of the inside cap are indicated by dots and the numeral 14 in Figure 2). Through the registering openings of the two caps the contents of the 25 receptacle may be dispensed. Since the inside cap is fixed in position, and the outside cap relatively rotatable, it is evident that the registry of the perforations in the inside and the outside caps may be readily destroyed by slight rotation of the outside cap, 30 whereby the bottle is again substantially sealed.

An important feature of the invention is the combination of an outside cap having a 35 screw-threaded or equivalent holding portion, cooperative with the correspondingly shaped exterior mouth portion of a receptacle, and a secondary cap of compressible material shaped to and holding itself in position over the receptacle mouth and upon the exterior mouth portion of the receptacle, the secondary cap sealing the receptacle, and acting as packing between the receptacle and the outside cap.

45 Inasmuch as many changes could be made in the above construction, and many apparently widely different embodiments of my invention could be made without departing from the scope thereof, it is intended 50 that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, 60 might be said to fall therebetween.

I claim:

1. A bottle or the like receptacle provided 65 exteriorly adjacent its mouth with a holding portion, and having a closure comprising an outside skirted cap with its top covering the

mouth of the receptacle, the skirted portion provided with a holding portion cooperative with the exterior holding portion of the receptacle, and a secondary skirted cap of hydrated cellulose shrunk onto the portion of 70 the receptacle which is covered by the closure and which is compressible between and relatively to the outer cap and the covered portion of the receptacle, the top of the secondary cap sealing the mouth of the receptacle and its skirt constituting a packing between the receptacle and the skirt of the outside cap. 75

2. A bottle or the like receptacle provided exteriorly adjacent its mouth with a threaded holding portion and having a closure comprising an outside skirted cap with its top perforated and covering the mouth of the receptacle, the skirted portion provided with a threaded holding portion cooperative 80 with the exterior threaded holding portion of the receptacle, and a secondary skirted cap of hydrated cellulose shrunk onto the portion of the receptacle which is covered by the closure and compressible between and 85 relatively to the outer cap and the covered portion of the receptacle, the top of the secondary cap sealing the mouth of the receptacle and its skirt constituting a packing between the receptacle and the skirt of the outside cap. 90

3. A bottle or the like receptacle provided exteriorly adjacent its mouth with a holding portion, and having a closure comprising an outside skirted cap with its top covering the 100 mouth of the receptacle, and a secondary skirted cap of hydrated cellulose shrunk onto the portion of the receptacle which is covered by the closure and compressible between and relatively to the outer cap and the 105 covered portion of the receptacle, the top of the secondary cap sealing the mouth of the receptacle and its skirt constituting a packing between the receptacle and the skirt of the outside cap and closely engaging the 110 holding portion exteriorly of the bottle mouth. 110

4. A bottle or the like receptacle provided exteriorly adjacent its mouth with a holding portion, a skirted cap covering the 115 mouth of the receptacle, the skirted portion of said cap provided with a holding means cooperative with the holding portion of the receptacle, and a compressible skirted member shrunk into sealing position over the 120 mouth of the receptacle with its skirted portion interposed between the holding portion of the receptacle and the holding means on said skirted cap. 120

5. A receptacle closure comprising an 125 outer rigid cap member having a skirted portion adapted to engage the side walls of the receptacle adjacent the open end thereof, and a compressible lining covering the side walls of the receptacle adjacent the open end 130

and forming a packing between the receptacle and the skirted portion of the rigid cap.

6. A receptacle closure comprising an outer rigid cap member having a skirted portion adapted to engage the side walls of the receptacle adjacent the open end thereof, and a compressible lining covering the open

end of the receptacle and extending down over the side walls of the receptacle and forming a packing between the receptacle and the rigid cap, said rigid cap having perforations through the top thereof.

In testimony whereof I affix my signature.

JOHN H. MONTGOMERY.
